UNITED STATES PATENT OFFICE.

HERMAN HARBORT, OF MADISON, WISCONSIN.

CHIMNEY-CLEANER.

1,329,596.

Specification of Letters Patent.

Patented Feb. 3, 1920.

Application filed April 17, 1919. Serial No. 290,755.

To all whom it may concern:

Be it known that I, HERMAN HARBORT, a citizen of the United States, residing at Madison, in the county of Dane and State 5 of Wisconsin, have invented a new and useful Chimney-Cleaner, of which the following is a specification.

My invention relates to chimney cleaners, the principal object being to provide a chimney 10 cleaning device which is adjustable to chimneys of different sizes.

A further object of the invention is to provide a chimney cleaning device which will thoroughly remove soot from the corners of 15 the chimney as well as the sides thereof.

Still another object of the invention is to provide a device of the above character which is removably mounted in the chimney and is raised and lowered from the outside 20 to perform the cleaning operation, thus the operator is prevented from being soiled by the falling soot.

An additional object of the invention resides in the provision of a chimney cleaning 25 device which is simple in construction, consists of few parts that may be readily assembled and disassembled, and which may be manufactured and sold at a minimum cost.

With the above and other objects and advantages in view the invention consists of 30 combinations of elements, arrangement of parts, constructions, and general assemblage which will be hereinafter specifically referred to and embraced in the subjoined 35 claims.

On the drawings, Figure 1 is a vertical sectional view of a chimney and showing my cleaner in operative position therein; Fig. 2 is a view showing the supporting 40 bracket for supporting the device in the chimney mounted on the upper end of the same, the bracket being shown in cross section; Fig. 3 is an elevation showing the operating pulley mounted in the lower end 45 of the chimney, the chimney being shown in cross section; Fig. 4 is a side elevation of one of the pulleys used in connection with my invention; Fig. 5 is a perspective of the device; and Fig. 6 is a perspective of one of 50 the heads and the parts connected therewith.

Referring to the drawing wherein like characters of reference designate like parts, the numeral 5 designates a horizontally disposed frame which is composed of a plurality 55 of radially disposed supporting members 6 having their outer ends slotted longitudi-

nally, this being indicated by the numeral 7. The frame 5 is provided with a central opening 7' that receives a cable or other flexible element to be hereinafter referred to. 60

Pivotedly mounted in each of the slotted ends of the supporting members 6 is a rod 8 having its upper end laterally curved. The rods on either side of the frame being curved in opposite directions. Heads 9 are 65 formed upon the upper ends of the rods 8 while their lower ends project below the frame 5 and each is connected with one of a plurality of contractile springs 10 which are radially disposed and connected together by 70 a ring 11 disposed beneath the frame 5.

Engaged with each of the heads 9 is a rod 12 having its medial portion looped and its ends extended in directions at right-angles to provide L-shaped members. The loop of 75 each L-shaped member is engaged with one of the heads 9 while the opposite legs of the rods 12 are disposed in parallelism. Expansile coil springs 13 are disposed upon the rods 12 and urge the rods 8 outwardly. 80 These springs 13 serve as cleaning elements as well as to urge the rods outwardly.

Secured in each of the slots of the frame 5 is a cable 14 all of which are extended upwardly and connected together and attached to a cable 15 which is engaged about a pulley 16 supported in a bracket 17 that is mounted upon the upper end of the chimney, the opposite end of the cable being extended around a pulley 18 in the lower end 90 of the chimney and thence secured in the opening 7' of the frame 5. This pulley 18 is fixed to rotate with a shaft 19 which is operated by a crank handle 20, the latter being operated to raise and lower the device to 95 perform the cleaning operation.

This construction is merely illustrative and in no sense am I limited to the construction as set forth, but that the present construction may be modified in many respects 100 and that the limits of such modification are only governed by the subjoined claims.

What is claimed is:

1. A chimney cleaner comprising a frame; a plurality of vertical rods pivoted intermediate their ends thereto; contractile coil springs one end of each being connected to one end of one of the rods, the other ends of the coil springs being connected at a common point to normally urge the pivoted rods into 105 engagement with the chimney; and cleaning implements supported by the rods. 110

2. In a chimney cleaner, a frame including a plurality of radially disposed supporting members having slots in their outer ends; vertical rods pivoted intermediate their lengths in the slots in the supporting members; L-shaped rods carried one by each of the vertical rods at its upper end, the adjacent legs of the L-shaped rods being disposed in parallel relation; expansible coil springs encircling the L-shaped rods; springs drawing the lower ends of the vertical rods toward each other; and means for raising and lowering the frame within a flue.
13. 3. A chimney cleaner comprising a frame; a plurality of vertical members pivoted intermediate their ends to the frame; cleaning means on the upper ends of said members; retractile springs connected at their outer ends with the lower ends of said members;

and means for uniting together the inner 20 ends of the springs.

4. A chimney cleaner comprising a frame; vertical members pivoted intermediate their ends on the frame; means connected with the lower ends of said members for swinging the upper ends of said members outwardly; L-shaped elements mounted at their angles on the upper ends of said members; and cleaning devices carried by the L-shaped elements.
